Patented Aug. 23, 1921.

FIG. 1.

FIG. 2.

Inventor:
George Kehl
By
Hunting. Atty.

UNITED STATES PATENT OFFICE.

GEORGE KEHL, OF CHICAGO, ILLINOIS.

GAME APPARATUS.

1,388,265.

Specification of Letters Patent. Patented Aug. 23, 1921.

Application filed June 24, 1920. Serial No. 391,410.

To all whom it may concern:

Be it known that I, GEORGE KEHL, a citizen of the United States, residing at Chicago, Cook county, Illinois, have invented 5 certain new and useful Improvements in Game Apparatus, of which the following, taken in connection with the drawings, is a description.

My invention has for its object the production of a game apparatus or puzzle whereby several movable members formed of different kinds of material are placed in a receptacle and designed to be arranged in specific positions with respect to a picture in 10 the bottom of said receptacle to complete 15 the outline of the character displayed in the picture.

A further object of my invention is to provide a game of this kind wherein the 20 movable members are each formed of different material, of different weights, of different colors, of different shapes; having different movements and each of which fits into a different sized and shaped depression formed in the bottom of the main receptacle.

25 A further object of the invention is to provide a simple and pleasing game or puzzle of this kind wherein the movable members may be manipulated only by the agitation 30 of the casing or receptacle in which they are contained to cause them to assume certain positions with respect to some other member, and with respect to the outline of the character of which they form a part.

35 With these and other objects in view, my invention consists of certain features of novelty in the construction, combination and arrangement of the parts hereinafter described in connection with the accompanying drawings and in these drawings:—

40 Figure 1 is a top plan view of my invention, and Fig. 2 is a vertical sectional view through the same.

In carrying out my invention A represents 45 a box like casing or receptacle which may be square, rectangular, or any other shape suited to the design to be displayed therein, and which may be formed of paper board, wood, sheet metal, or any other material suitable for the purpose. Fitting over the 50 top of this receptacle A is a transparent covering B such as glass, celluloid or like material, through which a picture arranged on the bottom of the casing, may be plainly seen.

55 The material forming the bottom A' of the receptacle is thicker than the sides thereof, as shown in Fig. 2. Arranged at differ-

ent places to suit the character illustrated are a plurality of counter-sunk depressions of different sizes and shapes to suit the 60 sizes, and shapes of different movable objects to be arranged therein.

To illustrate the idea of my invention I have in this instance shown the image of an intoxicated man, C, who is attempting to replace the cork in a bottle which is open. It will be understood of course that other images, to illustrate other ideas, may be used in place of this one and the movable members changed accordingly.

70 In this instance I have provided two depressions or counter-sunk receptacles a—a illustrating the eyes of the individual, one counter-sunk portion a' illustrating the nose, and one counter-sunk portion a'' illustrating 75 the cork which is to be replaced in the bottle. Corresponding to each of these depressions or counter-sunk portions are the balls b—b representing eyes, each of which in completing the puzzle must be seated in one of the 80 depressions a; a colored capsule c representing the nose is adapted to be seated in the depression a'; a cork d will be seated in the depression a'' connecting with the cork screw a'' ready to be replaced in the bottle a''. 85

The movable members b, c, and d are formed of different kinds of material, of different sizes and different shapes. Each of said members must be fitted into the depression corresponding to it in shape and 90 size, and considerable difficulty is experienced before the different members can be arranged in their proper places to complete the character illustrated, as in this instance the picture will represent a man with a large 95 red nose, blood shot eyes and with a facial expression which tells the entire story of his dissipation.

I claim:—

A device of the class described comprising 100 a box like casing, having a flat bottom displaying an image arranged therein, a transparent covering in said casing, the bottom of said casing having a plurality of different sized and shaped depressions arranged 105 therein in different relative positions, a plurality of rolling and tumbling members in said casing, said members being formed of different sizes and shape each adapted to fit in one of the aforesaid depressions to complete the character displayed in the casing. 110

In testimony whereof I have signed this specification.

GEORGE KEHL.
